UNITED STATES PATENT OFFICE.

GEORGE W. MOORMAN, OF EDINBURG, ASSIGNOR OF ONE-HALF TO MILTON F. MADDOX, OF INDIANAPOLIS, INDIANA.

BURIAL-CASKET LID.

SPECIFICATION forming part of Letters Patent No. 402,846, dated May 7, 1889.

Application filed August 4, 1888. Serial No. 281,937. (No model.)

To all whom it may concern:

Be it known that I, GEORGE W. MOORMAN, a citizen of the United States, residing at Edinburg, in the county of Johnson and State 5 of Indiana, have invented a new and useful Improvement in Burial-Casket Lids, of which the following is a specification.

My invention relates to an improvement in burial-casket lids.

10 The object of my improvement is to permit the withdrawal of a portion of the lid of the casket from the upper portions of a corpse placed therein without the removal of any portion of the lid from the casket, as herein- 15 after fully described.

The accompanying drawings illustrate my invention.

Figure 1 represents a view in perspective showing the lid closed. Fig. 2 represents a 20 similar view showing the lid open. Fig. 3 represents a central longitudinal section showing the lid open. Fig. 4 represents a similar section showing the lid closed. Fig. 5 represents a transverse section.

25 The casket-top A is of the usual raised form, having a central opening, B, extending nearly the whole length and width of the casket. Said central opening is closed by two lids, C and D.

30 Lid C is of suitable length to cover the lower part of the body of a corpse, and it is attached at each end to the top of the casket by short links *e e* and *f f*. Said links are pivoted at their opposite ends, respectively, to the body 35 of the casket and to the lid, and the edges of the lid are rabbeted, as at *h*, Fig. 3, so as to overlap the edges of the opening B, the whole arrangement being such that the lid may rest upon the edges of and tightly close the lower

40 part of the opening B, as in Figs. 1 and 4, or may be supported a short distance above the opening by the links *e e* and *f f*, as shown in Figs. 2 and 3.

The lid D is of suitable length to abut against

the upper end of lid C and complete the closing of the opening B. It is rabbeted on the edges, so as to rest upon the edges of the opening, and is provided at the upper end with a lug, *i*, which enters a corresponding depression, *j*, in the upper end of the body. 45

50 G is a glass plate arranged to slide longitudinally in grooves in the body of the casket below the lid and to cover the upper part of opening B.

In operation, it being desirable to expose 55 the face and upper portion of the corpse, lid C is raised and pushed slightly downward until links *e* and *f* become perpendicular, thus supporting the lid a short distance above the opening. Lid D is now slid along the edges 60 of the opening B underneath the lid C, thus uncovering the upper portion of the opening. When closed, the lug *i* on lid D enters the depression *j* and thus prevents the lifting of the lid, and lid C, being closed down, abuts against 65 the lower end of lid D and keeps it in position. The two lids may be further secured by a lock, L, mounted in one of the lids. By the use of this device the casket-lid may be opened for viewing the corpse with the least 70 possible disturbance, and without interfering with the decorations on the lower part of the lid.

I claim as my invention—

The combination, with the body of a casket, 75 of a casket-lid consisting of two sections, one of which is connected to the body of the casket by folding supports which are arranged to support the lid above the body of the casket and the other of which is arranged to slide 80 longitudinally beneath the first section when raised, substantially as and for the purpose specified.

GEORGE W. MOORMAN.
